OIL PURIFIER FOR INTERNAL-COMBUSTION ENGINES

Application filed October 23, 1924. Serial No. 745,379.

Our invention relates to mechanism for preventing the accumulation of unvaporized fuel in the lubrication oil of an internal combustion engine by removing any such unvaporized fuel as fast as it is deposited in the lubricating oil. The principal object of the invention is to provide mechanism which will maintain the lubricating oil of an internal combustion engine in a cool condition 10 and free from any dilution due to the result of condensation of a portion of the fuel in the engine, thereby maintaining uniform lubricating conditions in the engine and the maximum lubricating power of the oil. 15 As is well known to those skilled in the art, crank case dilution is one of the most troublesome problems confronting the automotive engineer. New lubricating oil, as it is put into a motor, is a comparatively 20 thick viscous fluid having high lubricating properties. If diluted with gasoline or kerosene, it becomes thin and watery and rapidly loses its lubricating qualities so that the wear on moving parts is increased and, if the dilution is sufficient, the burning out of the bearings, or any other dangerous conditions may 25 result. It is also well known that in running a cold engine and in starting and warming up a cold engine, unvaporized gasoline and 30 particularly the so-called "heavy ends" of the fuel pass the piston rings and drain into the lubricating oil, thereby diluting it. This dilution takes place very rapidly, particularly in cold weather. In fact, it is not uncommon 35 to find a dilution in excess of twenty-five per cent after a car has been run five hundred miles, even with new cars of high grade and of excellent workmanship. Accordingly it has been the practice of automobile manufacturers to recommend that the crank case be 40 drained and the oil replaced by fresh lubricating oil after every five hundred miles. This, of course, causes considerable expense to the owner, and, as is more important, the 45 changing of the oil is neglected with consequent injury to the working parts of the engine.

The apparatus comprising our invention provides simple effectual means for removing the vaporized fuel from the lubricating

oil in the crank case, cooling the oil after the unvaporized fuel has been removed and returning it again to the crank case in condition to be most effective in lubricating the working parts of the engine. The device includes no moving parts or valves and therefore is simple and reliable. The arrangement pumps oil directly from the sump or lowest chamber in the crank case to a chamber where it falls upon a plate, heated to the proper temperature by the exhaust gases, which distills off all unvaporized fuel and any moisture which may have accumulated in the oil. After this the oil drains into a cooler where it is cooled to a temperature suitable for use for lubrication and then it is restored to the crank case. The pump ordinarily employed to circulate the oil in the engine circulates the oil through the refining apparatus, and therefore no complications are added to the structure.

The invention will be fully understood from the following description when taken in connection with the accompanying drawings, and the novel features thereof will be pointed out and clearly defined in the claims at the close of the specification.

Referring to the drawings:

Fig. 1 is an elevation partly in section of an automobile engine to which is applied the oil purifying apparatus embodying our invention.

Fig. 2 is an end view of the essential parts of the apparatus.

Fig. 3 is a detail of the construction of the upper part of the vaporizing chamber.

In the drawings at A is shown a cylinder block of an engine of standard construction, the crank case is shown at B and the oil pan at C. This oil pan has a sump or lower compartment D and troughs, one of which is shown at E, in which the ends of the connecting rods, not shown, dip to splash the oil, the lubricating system shown being of the type known as a circulating splash system. The oil is circulated by an oil pump F which draws oil from the bottom of the sump D and causes it to be delivered into the guide G, which directs it over a sprocket wheel H and chain I. The oil which falls down from the sprocket wheel H and chain I accumulates

in the bottom of the housing J and thence flows as shown at K into the trough E from which it is circulated to the successive troughs by the action of the several dippers secured to the connecting rods, not shown. The foregoing parts merely illustrate one well known type of automobile engine to which our invention is directly applicable.

In accordance with the invention, as applied to the engine above described, the oil drawn from the sump D through the pipe 11 by the pump F passes through the pipe 12 to a vaporizing chamber 13, preferably made integral with the exhaust manifold L of the motor. This chamber has a relatively short and steeply inclined bottom or lower wall 14, which separates it from the exhaust passage 15, through which the highly heated products of combustion escape from the cylinders. The oil from the pipe 12 drops directly on the highly heated inclined surface 14 and the gasoline, kerosene, or other "heavy ends" of fuel which are vaporizable are immediately vaporized, as suggested by the arrows in Fig. 1. At 16 (see Figs. 1 and 3) is shown an air passage closed by a screen which connects the vaporizing chamber 13 with a box 17, surrounding the exhaust manifold L and connected by the pipe 18 (Fig. 2) with the intake of the carburetor. The vapors which are distilled off from the lubricating oil escape through the passage 16 into the air stream, flowing to the carburetor (not shown) and thus enter the engine.

It will be observed that the surface 14 constitutes a short steeply inclined plate-like element exposed continuously to the heat of the exhaust gases, and along which the oil may gravitate at a speed which is proportioned to (1) the heat of the surface and (2) the viscosity of the oil. Moreover, the surface is so disposed and formed that the oil does not accumulate in a body thereon, but when dropped from the pipe 15 may assume a drop-like or globular form, or if extremely thin, because of dilution, spread out into a film, thereby to receive the full effect of the heat. It will be understood that in apparatus of this character, it is necessary that the oil be heated sufficiently to vaporize the fuel diluents therein, but not sufficiently to break up the oil itself. This object is effectively accomplished by a heated surface of plate-like form, on which the oil does not accumulate in a body or stream, but freely gravitates therealong in drop-like or film form.

In devices heretofore provided, the regulation of heat has been accomplished by the provision of a separate heating system or element, as distinguished from direct use of the exhaust manifold or a wall of the latter, as in the construction above described. Moreover, in such devices, it has been customary to regulate the amount of heat by manually or thermostatically operated valves which

direct a greater or less proportion of the hot exhaust gases from the manifold to the heating element, in order to maintain in the heating element a constant temperature irrespective of the temperature of the engine. We have found, however, that such control is unnecessary, and that with a construction such as described, it is practicable to rely upon the heat of the surface and the viscosity of the oil as the controlling factors, providing the oil is not accumulated in a body of considerable depth. Therefore, it is possible to eliminate these controlling mechanisms which add complexity to the power plant. It has been found in the operation of this system that due to the steep incline of the surface 14, the contact of the oil with the surface is very brief, but due to the fact that the oil is exposed to the surface in a thin film or drop-like form, this period of subjection of the oil to the heat is sufficient to vaporize the fuel diluents. It will be understood that the thinner the oil and the hotter the surface, the more rapidly will the oil pass, by gravity over the surface.

It will be observed, furthermore, that the oil is dropped in a substantially vertical plane upon the surface adjacent its upper end and unless the oil is extremely thin, it will travel along in drop-like or globular form, and will not remain in contact with the surface for such time which would cause the oil itself to break up.

After passing from the vaporizing chamber 13, the purified oil flows into a spiral trough 19 in a cooler 20, which is preferably constructed from aluminum on account of its high conductivity. The cooler 20 and its cover 21 are both provided with cooling fins 22, to increase the radiation. The cooler is preferably located immediately behind the fan of the engine so that the incoming stream of cool air will play directly on the oil and reduce its temperature as much as possible. After the purified and cooled oil passes down through the cooler it is conveyed by the pipe 23 to the guide G and returned to the circulating system of the engine as previously described.

From the foregoing description of the devices embodying our invention, it will be seen that all vaporized fuel present in the lubricating oil is removed in the vaporizing chamber, and that the oil is thoroughly cooled and will have recovered its viscosity before being reintroduced into the oil lubricating system of the engine. It will also be seen that the system is free from moving parts, valves, control devices and the like, so that the operation of the device will be continuous as long as the engine is running, and, furthermore, that it is not likely to get out of order in operation. Another important feature of the invention is that it purifies all the oil in the system and removes any unvaporized fuel which has

reached the sump, and does not, as do some devices already devised, merely purify the oil vapor in the crank case or cylinder.

What we claim is:

- 5 1. In combination with an internal combustion engine, an exhaust manifold therefor, a chamber heated by said exhaust manifold, an oil pump drawing oil from the sump of the engine and delivering it to said chamber, a box enclosing said chamber and manifold, said chamber having a vapor outlet communicating with said box, a carburetor air intake communicating with said box, a cooler communicating with said chamber and receiving oil therefrom, and return connections delivering the oil from the cooler to the lubricating system of the engine.
- 10 2. In an internal combustion engine having a lubricating system, an exhaust manifold provided with an integral wall the outer surface of which is inclined and forms the bottom of a chamber, said wall being exposed continuously to the full heat of the exhaust gases in the manifold, means for withdrawing oil from said system and directing the same upon the upper end of said inclined surface, said surface being disposed so that the oil may gravitate down the same without accumulating in a body thereon at a rate 15 of flow proportioned to the intensity of the heat of the surface and to the thickness of the oil, and a return connection from the lower end of said surface to said system.
- 20 3. In an internal combustion engine having a lubricating system, an exhaust manifold provided with a wall, the outer surface of which is inclined and forms the bottom of a chamber, said wall being exposed continuously to the full heat of the exhaust gases in the manifold, means for withdrawing oil from 25 said system and dropping the same upon the upper end of said inclined surface, whereby the oil may gravitate down said surface at a rate of flow proportioned to the intensity 30 of the heat of the surface and to the thickness of the oil, said surface being substantially plane whereby the oil dropped thereon may assume a drop-like form and unimpededly and without accumulation gravitate along 35 said surface, and a return connection from the lower end of said surface to said system.

In testimony whereof we affix our signatures.
